INTERLOCKING SYSTEM FOR RAILROADS

Sedgwick N. Wight, Rochester, N. Y., assignor to
General Railway Signal Company, Rochester,
N. Y.

Application October 16, 1934, Serial No. 748,481

8 Claims. (Cl. 246—134)

This invention relates to interlocking systems for railroads and it more particularly pertains to a system in which the interlocking is accomplished by electrical isolation.

5 In interlocking traffic controlling devices in an interlocking system it is necessary to so interlock the various traffic controlling devices that conflicting routes cannot be set up.

The present invention is particularly applicable 10 to a railroad crossing with provision of route circuit portions which conform with the various portions of the track layout, so organized that the clearing of signals for particular directions of traffic over the route represented by the route 15 circuit is effective to prevent the clearing of signals for traffic in a conflicting direction.

More specifically, one route relay circuit is employed to control both routes over a railway crossing and means are provided in connection 20 with the signal clearing circuits requiring all signals to be at stop before a given signal can be cleared. Interlocking of the signal clearing relays is such that only one signal can be cleared at any one time.

25 The present invention is shown applied to a railway crossing having no switches. An important feature of the invention is the application of the route relay principle disclosed in my prior application Ser. No. 540,596, filed May 28, 1931, 30 to such a railway crossing. In this connection it will be apparent that the invention may be applied to a track layout of the form illustrated in Fig. 2, that is, the crossing signals may be controlled as specifically illustrated in Fig. 1 with 35 the signals for the turnouts, cross-overs, and the like, of each railroad interlocked with the associated switches in a grouping arrangement such, for example, as shown in the prior application of A. Langdon, Ser. No. 739,977, filed August 15, 40 1934.

Apparatus

The track layout of Fig. 1 includes a railroad crossing which, for convenience in describing the 45 present invention, is referred to as section 1—2 which crosses section 3—4.

The signalling arrangement provided as a typical example comprises signal 1S for governing west bound traffic over section 1—2, signal 2S for 50 governing east bound traffic over section 1—2, signal 3S for governing west bound traffic over section 3—4 and signal 4S for governing east bound traffic over section 3—4. These signals are illustrated as being of the color light signal type although they may be of any other suitable

type governed in accordance with the present invention by associated lever repeating relays 1GZ, 2GZ, 3GZ and 4GZ.

The condition of occupancy of the various track sections is preferably repeated in the tower by 5 track relays or track repeating relays, but for convenience in describing the invention applied to the track layout of Fig. 1 the detailed circuits of such relays have been omitted from the drawing. Such track sections into which the track is 10 divided by suitable insulated joints are assumed to have track circuits of the usual closed circuit type. While the detailed track relay circuits are not shown, relay T is the normally energized track relay for the section of track comprising 15 the crossing. Relays T20, T40, T30 and T10 are the normally energized track relays for the approach sections adjacent to sections 2, 4, 3 and 1 respectively.

Relays G are associated with their respective 20 signals as designated by the numerals preceding their letter reference characters. Each of these relays when deenergized causes its associated signal to indicate stop but when energized causes its associated signal to indicate proceed, subject 25 to traffic conditions in accordance with the usual practice.

Relays GZ are associated with their respective 30 signals levers as designated by the numerals preceding their letter reference characters. Levers 35 SGL (with suitable preceding numerals) govern the corresponding signals subject to the interlocking operation as will be pointed out in detail later.

A time element thermal relay TR and an associated stick relay S are shown cooperating with signal relays G to control signal controlling relays GZ for delaying the clearing of a signal for a predetermined time after signals are restored to stop. 40

Operation

Normal conditions.—The signal control levers are usually returned to normal "at stop" positions as shown in Fig. 1 so that the respective signals display stop indications. More specifically, the red lamp of signal 1S for instance is energized over a circuit extending from (+), back contact 10 of relay 1G and the red lamp of signal 1S, to (—). A similar circuit is effective for lighting the red lamp of signal 2S extending from (+), through back contact 22 of relay 2G. A similar circuit is effective for lighting the red lamp of signal 3S extending through back contact 12 of relay 3G. A similar circuit is effective 55

for lighting the red lamp of signal 4S extending through back contact 13 of relay 4G.

With the track sections unoccupied, the track relays are normally energized but since the detailed circuit arrangement for maintaining these relays energized is familiar to those skilled in the art it is believed unnecessary to show these detailed track circuits.

With the signal control levers in their "at stop" positions, the time element stick relay is energized over a circuit extending from (+), winding of relay S, front contact 14 of relay S, heating element 15 of relay TR, back contacts 16, 17, 18 and 19 of relays 3G, 1G, 4G and 2G respectively, to (-). With track relays T20, T40, T30 and T10 all picked up a shunt circuit is completed around front contact 14 of relay S which extends through normally closed front contacts 21, 41, 31 and 11 of these respective T 20 relays.

Signal control.—An explanation will now be given of the individual control of the signals by their respective levers, subject to route control and time locking, which features will be described 25 later in the specification.

For example, assuming the system to be in its normal condition as illustrated, the actuation of lever 1SGL to its clear position closes a circuit for picking up relay 1GZ which extends from (+), contact of lever 1SGL in its right hand dotted position, back contact 23 of relay 3GZ, winding of relay 1GZ, back contact 24 of relay 13RR, conductor 50, front contact 25 of relay S, contact 26 of relay TR in its left hand position, back contacts 16, 17, 18 and 19 of relays 3G, 1G, 4G and 2G respectively, to (-). The response of relay 1GZ completes its stick circuit including front contact 27, thereby rendering relay 1GZ wholly dependent upon the lever 1SGL in the 40 event that route relay 13RR, is picked up in response to the energization of relay 1GZ, provided the route is established and proper to be cleared as will now be described.

Relay 13RR is energized over a circuit extending 45 from (+), back contact 28 of relay 2GZ, back contact 29 of relay 4GZ, windings of relays 24RR and 13RR in series and front contact 32 of relay 1GZ, to (-). Both relays 13RR and 24RR are picked up over this circuit.

50 Relay 1G is energized over a circuit extending from (+), front contact 33 of relay T, front contact 34 of relay 13RR, front contact 35 of relay 1GZ and winding of relay 1G, to (-). The picking up of relay 1G opens the stick circuit of relay S at back contact 17 and at contact 10 switches the energizing circuit from the red to the green lamp of signal 1S, thereby causing signal 1S to give a proceed indication.

From the above it is apparent that the operation 60 of a signal lever so conditions the route circuits that the signal will be cleared which is associated with the operated signal lever if it is proper for such signal to be cleared. This conditioning of the route circuit also prevents opposing signal levers from being effective, since the picking up of the route relay 24RR prevents the picking up of either relay 2GZ or 4GZ. The picking up of relay 13RR also prevents the energization of relay 3GZ, all of which is effective 65 to prevent the clearing of conflicting signals.

This part of the description more particularly points out how a particular signal lever functions to condition a route circuit and how the response of such route circuit governs the response of the associated signal. The pick up 70

and stick circuits for each GZ relay and the energizing circuit for each G relay will now be pointed out.

The pick up circuit for relay 2GZ extends from (+), contact of lever 2SGL in its right hand dotted position, winding of relay 2GZ, back contacts 36 and 37 of relays 4GZ and 24RR in series, conductor 50, front contact 25 of relay S, contact 26 of relay TR in its left hand position, back contact 16, 17, 18 and 19 of relays 3G, 1G, 4G and 2G respectively, to (-). The stick circuit for relay 2GZ is completed through its front contact 38.

The picking up of relay 2GZ closes a circuit for picking up route relays 24RR and 13RR in series extending from (+), back contact 39 of relay 3GZ, back contact 32 of relay 1GZ, windings of relays 13RR and 24RR in series, back contact 29 of relay 4GZ and front contact 28 of relay 2GZ, to (-).

A circuit is closed for picking up relay 2G which extends from (+), front contact 33 of relay T, front contact 42 of relay 24RR, front contact 43 of relay 2GZ, and winding of relay 2G, to (-). When relay 2G is picked up, the switching of contact 22 removes the stop indication of signal 2 and establishes its proceed indication.

The pick up circuit for relay 3GZ extends from (+), contact of lever 3SGL in its right hand dotted position, winding of relay 3GZ, back contacts 44 and 45 of relays 1GZ and 13RR in series, conductor 50 and over the remainder of the previously described circuit, to (-) at back contact 19 of relay 2G. Relay 3GZ establishes its stick circuit at its front contact 46.

The picking up of relay 3GZ closes a circuit for picking up relays 13RR and 24RR in series which extends from (+), back contacts 28 and 29 of relays 2GZ and 4GZ respectively, windings of relays 24RR and 13RR, back contact 32 of relay 1GZ and front contact 39 of relay 3GZ, to (-).

Relay 3G is picked up over a circuit extending from (+), front contact 33 of relay T, front contact 34 of relay 13RR, front contact 47 of relay 3GZ and winding of relay 3G, to (-). The switching of contact 12 of relay 3G deenergizes the red indicator of signal 3S and energizes the green or proceed indicator of this signal.

The pick up circuit of relay 4GZ extends from (+), contact of lever 4SGL in its right hand dotted position, back contact 48 of relay 2GZ, winding of relay 4GZ, back contact 49 of relay 24RR, conductor 50 and over the previously described circuit, to (-) at back contact 19 of relay 2G. Relay 4GZ establishes its stick circuit at its front contact 51.

The picking up of relay 4GZ closes a circuit for picking up relays 24RR and 13RR in series which extends from (+), back contacts 39 and 32 of relays 3GZ and 1GZ respectively, windings of relays 13RR and 24RR and front contact 29 of relay 4GZ, to (-).

Relay 4G is energized over a circuit extending from (+), front contact 33 of relay T, front contact 42 of relay 24RR, front contact 52 of relay 4GZ and winding of relay 4G, to (-). The switching of contact 13 of relay 4G changes the indication of signal 4S from red to green.

The above description points out the detailed circuits for clearing any one of the four signals illustrated. It will be apparent that a signal can only be cleared when all signals are at stop, because the pick up circuits for the GZ relays in-

clude conductor 50 which is deenergized by the opening of some one of the contacts 16, 17, 18 and 19 when any signal is cleared. It will also be apparent that only one signal of the group can be cleared at any one time, since the picking up of a G relay opens the above described pick up circuit for the GZ relays. In addition to this, relays 1GZ and 3GZ are interlocked with each other, that is, the picking up of either one of these relays opens the pick up circuit of the other. Similarly, relays 2GZ and 4GZ are interlocked with each other since the opening of back contact 48 of relay 2GZ opens the pick up circuit of relay 4GZ and the opening of back contact 36 of relay 4GZ opens the pick up circuit of relay 2GZ. Furthermore, when a route circuit has been established by the picking up of the route relays 24RR and 13RR in response to the picking up of the GZ relay, the pick up circuits 20 of all GZ relays are opened at back contacts 24, 37, 45 and 49 of the RR relays. The only GZ relay energized is the one that was picked up to establish its above described stick circuit.

Time release.—In order to allow sufficient time for a train approaching a signal to stop after such signal has been restored to a stop condition before another signal can be cleared, a time release feature has been provided.

Upon the picking up of any one of the G relays, 30 the energizing circuit of relay S is opened allowing this relay to drop away. Then upon the closure of the back contact of the G relay (upon its release for restoring the associated signal to stop), energy is applied to the thermal relay TR over a circuit extending from (+), back contact 14 of relay S, heating element 15 of relay TR, 35 back contacts 16, 17, 18 and 19 of relays 3G, 1G, 4G and 2G respectively, to (—). The current flowing in this circuit causes the thermal relay TR to close its right hand contact 26 after a predetermined time, which is effective to pick up relay S over a circuit extending from (+), winding of relay S, right hand contact 26 of relay TR, 40 back contacts 16, 17, 18 and 19 of relays 3G, 1G, 4G and 2G respectively, to (—). The picking up of relay S opens the direct circuit to (+) at its back contact 16 which deenergizes thermal relay TR. Relay TR slowly shifts its contact 26 from the right to the left and relay S maintains 45 itself energized over the above described stick circuit including the heating element of relay TR, but since the resistance of the winding of relay S is high, the value of the current which flows through heating element 15 is not sufficient to prevent this relay restoring to normal.

As soon as contact 26 is closed in its left hand position, conductor 50 is supplied with (—) potential so that a GZ relay may be energized in response to its lever movements. From this it is 60 seen that the response of a G relay to clear a signal, followed by the restoration of the associated signal lever to normal (which puts this signal to stop) causes a predetermined time to be measured off by relay TR before this or any other signal can be cleared.

Such an arrangement serves to prevent the quick reversal of traffic direction or the quick shifting of clear signals for conflicting routes by the quick manipulation of the signal levers, 65 thereby giving adequate protection to the movement of trains over the track section illustrated.

Front contacts 21, 41, 31 and 11 of relays T20, 70 T40, T30 and T10 respectively are shown connected to the time element circuit in such a way 75 that the time delay in clearing a subsequent sig-

nal as above described is eliminated. In the event that there is no train in any of the sections adjacent to the illustrated section, then it is unnecessary to include this delayed action in the operation of the signals.

With all of these adjacent track sections unoccupied relays T20, T40, T30 and T10 will be picked up so that when a cleared signal is restored to its stop condition, a circuit for immediately picking up relay S is effective which extends from (+), winding of relay S, front contacts 11, 31, 4, and 21 of relays T10, T30, T40 and T20 respectively, back contacts 16, 17, 18 and 19 of relays 3G, 1G, 4G and 2G respectively, to (—). Since relay S is immediately picked up under the above condition, the removal of (+) from the heating element of relay TR at back contact 14 of relay S prevents the operation of relay TR and therefore the circuit for the GZ relays is retained intact at contact 26 in its left hand position.

Having thus described an interlocking system as one specific embodiment of the present invention it is to be understood that various modifications, adaptations and alterations may be applied to meet the requirements of practice without in any manner departing from the spirit or scope of the invention except as limited by the appended claims.

What I claim is:—

1. In a traffic controlling system for railroads, a first stretch of track, a second stretch of track intersecting said first stretch of track, signals governing the entrance of traffic into said stretches of track in both directions, an individual control lever for each of said signals for clearing the associated signal, interlocking means allowing only one of said signals to be cleared at any one time, and a single delay means for all of the signals allowing each signal to be cleared only a predetermined time after one of said signals has been put to stop.

2. In a traffic controlling system for railroads, a first stretch of track, a second stretch of track intersecting said first stretch of track, a third stretch of track adjacent one of the other stretches of track, a track relay controlled over said third stretch of track, signals governing the entrance of traffic into said first and second stretches of track in both directions, an individual control lever for each of said signals for clearing the associated signal, interlocking means allowing only one of said signals to be cleared at any one time, a single delay means allowing each signal to be cleared only a predetermined time after one of said signals has been put to stop, and means controlled by said track relay for disabling said delay means.

3. In a traffic controlling system for railroads, a first stretch of track, a second stretch of track intersecting said first stretch of track, signals governing the entrance of traffic into said stretches of track in both directions, a signal control lever for each of said signals and having clear and stop positions, means associated with each of said levers and its respective signal for clearing said signal when its associated lever is in its clear position, interlocking means allowing only one of said signals to be cleared at any one time, and a single means for automatically delaying the clearing of any of said signals for an appreciable time after one of said signals has been restored from a clear to a stop condition.

4. In an interlocking system for railroads, a pair of intersecting track sections, signals govern-

- ing traffic both ways over said sections, levers corresponding to said signals, a route control circuit comprising means for controlling said signals, means responsive to the actuation of one 5 of said levers to its clear position for energizing said route control circuit only when all other levers are in their stop positions, means responsive to the energization of said route control circuit for clearing the signal corresponding to the 10 actuated lever, and a single means for automatically delaying the clearing of any of said signals for a predetermined time after one of said signals has been restored from a clear to a stop condition.
- 15 5. In a railroad crossing, two stretches of track crossing each other, a signal at the entrance of each end of each stretch, a signal relay to control each signal, a manually operable lever for controlling each signal, a lever relay for each 20 lever, a route circuit energized upon the picking up of one and only one of the lever relays, each signal relay having an energizing circuit requiring, for its energization, that the route circuit be energized and a front point of the corresponding lever relay be closed, each lever relay having a pick-up circuit including a back point of each of the signal relays.
- 25 6. In a railroad crossing, two stretches of track crossing each other, a signal at the entrance of each end of each stretch, a signal relay to control each signal, a manually operable lever for controlling each signal, a lever relay for each lever, a route circuit energized upon the picking up of one and only one of the lever relays, each 30 signal relay having an energizing circuit requiring, for its energization, that the route circuit be energized and a front point of the corresponding lever relay be closed, each lever relay having a pick-up circuit including a back point of each of the signal relays, and the back point of another lever relay requiring for its energization that the route circuit be de-energized, the energizing pick-up circuit for each lever relay including a time contact 35 opened upon the clearing of a signal and time measuring means for causing the time contact to close upon putting the signal to stop only after the elapse of a predetermined time.

tion that the route circuit be de-energized.

7. In a railroad crossing, two stretches of track crossing each other, a signal at the entrance of each end of each stretch, a signal relay to control each signal, a manually operable lever for controlling each signal, a lever relay for each lever, a route circuit energized upon the picking up of one and only one of the lever relays, each signal relay having an energizing circuit requiring, for its energization, that the route circuit be energized and a front point of the corresponding lever relay be closed, each lever relay having a pick-up circuit including a back point of each of the signal relays, the energizing pick-up circuit for each lever relay including a time contact 10 opened upon the clearing of a signal and time measuring means for causing the time contact to close upon putting the signal to stop only after the elapse of a predetermined time.

15 8. In a railroad crossing, two stretches of track crossing each other, a signal at the entrance of each end of each stretch, a signal relay to control each signal, a manually operable lever for controlling each signal, a lever relay for each lever, a route circuit energized upon the picking 20 up of one and only one of the lever relays, each signal relay having an energizing circuit requiring, for its energization, that the route circuit be energized and a front point of the corresponding lever relay be closed, each lever relay having a pick-up circuit including a back point of each of the signal relays, and the back point of another lever relay requiring for its energization that the route circuit be de-energized, the energizing pick-up circuit for each lever relay including a time contact 25 opened upon the clearing of a signal and time measuring means for causing the time contact to close upon putting the signal to stop only after the elapse of a predetermined time.

30 SEDGWICK N. WIGHT.
